UNITED STATES PATENT OFFICE

GEORGE P. CRYSLER, OF CHICAGO, ILLINOIS

FURNACE SETTING AND CONTROL

Application filed September 16, 1927. Serial No. 219,838.

The invention relates to improvements in furnace settings and means for controlling the flow and volume of air and steam through the conduits and openings provided therein.

5 In my co-pending application for furnace wall linings or facings, Serial No. 198,378, filed June 13, 1927, I have shown and claimed a novel lining for a furnace wall of a character similar to that herein disclosed. The 10 present application has more to do with means for regulating the drafts of air and steam that pass through the various channels or conduits into the furnace for supporting combustion and for proportioning 15 the air passing through the grates, below the fire, and the said conduits, especially when a forced draft is used to promote combustion.

One of the objects of the invention is to 20 provide a very durable furnace lining in conjunction with fluid regulating means adjustable to produce conditions of operation which will effect desirable results with an attendant economy in fuel consumption.

Other objects, advantages and benefits will 25 hereinafter appear, to persons skilled in the art, from a consideration of the following description when taken in conjunction with the drawings forming a part hereof, wherein:

30 Figure 1 is a front elevation of a furnace setting for a steam boiler with my improvements shown in connection therewith.

Figure 2 is a plan section of a fragment taken on line II-II of Figure 1.

35 Figure 3 is a broken away section of one side of the interior of the setting.

Figure 4 is an enlarged vertical section taken substantially on line IV-IV of Figure 1.

40 In all the views the same reference characters are used to indicate similar parts.

In the drawings, 5 is a furnace front with which my invention is shown to be associated. 6-6 are the doors to the combustion 45 chamber or firing doors and 7-7 are the doors to the ash pit. The fuel supporting grates, as in all similar types of boiler and furnace settings, are placed interiorly and between the upper edge of the ash doors 7-7 and the lower edge of the fire doors 6-6.

These grates are not shown because they are necessarily concomitant parts of all similar structures.

The lining blocks 8-8 are easily removable, as fully explained in my aforesaid co-pending application and each block has a transversely extending aperture 9 which communicates with a horizontal branch air or supplemental conduit 10. The conduit 10 communicates with the horizontal trunk air 55 conduit or duct 11 made in the wall 12, through the vertical conduits 13, provided by channels 14 in the rear surfaces of the back blocks 15, and thru the horizontal perforations 16-16 extending rearwardly in 60 the blocks 8 from the conduits 10. The trunk air conduit 11 has an opening 17 which is in communication with the ash pit below the grates of the furnace.

The opening 17 may be closed by a flap 70 valve, or damper 18, which swings on an axis 19 and which is movable to open wide the opening 17 and to close the trunk conduit 11, in rear of the vertical conduits 13, as shown by broken lines at 20. When the damper is 75 in position 20, all of the air from conduit 11 will enter the ash pit below the grates.

It is apparent that when the valve 18 is in position shown in full lines in Figure 4, all of the air from trunk conduit 11 will ascend the 80 tubes or conduits 13 and that none of it will enter the ash pit below the grates. The damper 18 may be moved to intermediate positions to send any portion of the air through either or both of the described paths. A rod 21 is an 85 extension of the axis for the valve 18 and extends into the ash pit, and secured to its outer end a crank arm 22 is movable by rod 23 to open and to close the valve 18. A casting 24 is secured at the mouth of the trunk conduit 90 11. A steam chamber 25 surrounds the opening 26 in the casting 24.

A sliding door, or valve 27 is movable vertically to open or to close the opening 26 to admit a larger or smaller volume of air into 95 the trunk conduit 11. There is a structure, such as herein described, on each side of the setting and a similar arrangement may be combined entirely within the furnace and intermediate the side walls.

A chain 30 passes over pulleys 31 and is secured at one end to the valve 27 and at its other end to a balancing weight 32.

A steam pipe 35 is contained in air conduit 10. At suitable intervals and opposite the inner ends of the lateral openings 9 it has spraying nozzles 36 whereby to spray steam and to draw air through the openings 9 into the combustion chamber. The steam pipe 36 is suitably connected to the boiler 38 and is controlled by the globe valve 37. When a forced draft is desired, an electric motor 40 and fan 41 may be placed in the opening 26 to force air into the trunk conduit 11. The relative volume of air passing into the combustion chamber may be regulated by valve 18 and the volume of steam may be regulated by valve 37 and the aggregate volume of air admitted into the trunk conduit may be controlled by valve 27.

This arrangement, when properly used, is efficient and the furnace is entirely smokeless. When steam is expanded, as when issuing from a spraying nozzle, its temperature is somewhat reduced, but, in this environment, the temperature of the steam is raised by its impact into contact with the incandescent blocks 8 as it passes through the orifices 9.

I am aware that many changes may be made, and numerous details of construction may be varied through a wide range without departing from the principles of this invention, and I therefore do not purpose limiting the patent granted hereon, otherwise than necessitated by the prior art.

I claim:

1. A furnace comprising masonry walls and a boiler supported thereby, said walls forming a combustion chamber and an ash pit, each of the side walls of said furnace having a longitudinally extending trunk duct therein and a plurality of vertical ducts communicating with said trunk duct throughout its length, said side walls each having supplemental, horizontally disposed, vertically spaced longitudinal ducts therein arranged above said trunk duct and nearer the inner faces of said walls the walls constructed to provide a plurality of horizontally disposed passages between said vertical ducts and said supplemental ducts and a less number of lateral openings between said supplemental ducts and the combustion chamber.

2. A furnace comprising masonry walls and a boiler supported thereby, said walls forming a combustion chamber and an ash pit, each of the side walls of said furnace having a longitudinally extending trunk duct therein and a plurality of vertical ducts communicating with said trunk duct throughout its length, said side walls each having supplemental, horizontally disposed, vertically spaced longitudinal ducts therein arranged above said trunk duct and nearer the inner faces of said walls, there being a plurality of

horizontally disposed passages between said vertical ducts and said supplemental ducts and a less number of lateral openings between said supplemental ducts and the combustion chamber, and a valve between the ends of said trunk duct and the first of said vertical ducts for regulating the volume of air passing to said vertical ducts.

3. A furnace comprising masonry walls and a boiler supported thereby, said walls forming a combustion chamber and an ash pit, each of the side walls of said furnace having a longitudinally extending trunk duct therein and a plurality of vertical ducts communicating with said trunk duct throughout its length, said side walls each having supplemental, horizontally disposed, vertically spaced longitudinal ducts therein arranged above said trunk duct and nearer the inner faces of said walls, there being a plurality of horizontally disposed passages between said vertical ducts and said supplemental ducts and a less number of lateral openings between said supplemental ducts and the combustion chamber, each of said side walls having a horizontal duct between said trunk duct and the ash pit disposed near the entrance to said trunk duct, and a valve arranged to control air passing to said horizontal duct and also to said vertical ducts, and a valve at the entrance to each of said trunk ducts.

4. A furnace comprising masonry walls and a boiler supported thereby, said walls forming a combustion chamber and an ash pit, each of the side walls of said furnace having a longitudinally extending trunk duct therein and a plurality of vertical ducts communicating with said trunk duct throughout its length, said side walls each having supplemental, horizontally disposed, vertically spaced longitudinal ducts therein arranged above said trunk duct and nearer the inner faces of said walls, there being a plurality of horizontally disposed passages between said vertical ducts and said supplemental ducts and a less number of lateral openings between said supplemental ducts and the combustion chamber, and a steam pipe in each of said supplemental ducts having outlets aligned with the lateral openings between said supplemental ducts and the combustion chamber.

5. A furnace comprising masonry walls and a boiler supported thereby, said walls forming a combustion chamber and an ash pit, each of the side walls of said furnace having a longitudinally extending trunk duct therein and a plurality of vertical ducts communicating with said trunk duct throughout its length, said side walls each having supplemental, horizontally disposed, vertically spaced longitudinal ducts therein arranged above said trunk duct and nearer the inner faces of said walls, there being a plurality of horizontally disposed passages between said vertical ducts and said supplemental ducts

and a less number of lateral openings between said supplemental ducts and the combustion chamber, and a heating chamber about the entrance to each trunk duct.

5 6. A furnace comprising masonry walls and a boiler supported thereby, said walls forming a combustion chamber and an ash pit, each of the side walls of said furnace having a longitudinally extending trunk duct therein and a plurality of vertical ducts communicating with said trunk duct throughout its length, said side walls each having supplemental horizontally disposed vertically spaced longitudinal ducts therein arranged
10 above said trunk duct and near the inner faces of said walls, the walls being constructed to provide a plurality of horizontally disposed passages between said vertical ducts and said supplemental ducts, and a plurality of lateral
15 openings between said supplemental ducts and the combustion chamber.

In testimony whereof I have hereunto subscribed my name at Chicago, Cook County, Illinois.

25 GEORGE P. CRYSLER.
